UNITED STATES PATENT OFFICE

2,440,816

AIR-COOLED ELECTRODE HOLDER

Louis D. Abramson, Boston, Mass.

Application November 1, 1945, Serial No. 625,992

1 Claim. (Cl. 219—8)

1

My invention as described herein, and illustrated in the accompanying drawings, consists of an electrode holder for use in electric welding operations, an object of which is to provide means for dissipation of the great heat generated in the holder.

Another object of my invention is to provide an air cooled electrode holder.

A further object of this invention is properly to seat in the holder electrodes of various diameters.

A still further object of the invention is the provision of means whereby an electrode of any diameter may be instantly and securely gripped through a part turn of the holder handle.

Other features and advantages will become more readily apparent from the following description and the accompanying illustrative drawings in which:

Figure 1 is a longitudinal sectional view of my holder.

Figure 2 is a section on line 2—2 of Figure 1, the electrode removed.

Figure 3 is a detail of a jaw actuating sleeve, and

Figure 4 is an elevational view of an electrode gripping device shown attached, the handle partly broken away.

In the accompanying drawings, and in the following specification, the same reference characters are used to designate the same parts and elements throughout and in which 10, refers to my invention in its entirety and 11, indicates a housing which is provided with numerous perforations 12, for free circulation of air into its chamber 13. Mounted within the chamber 13, is a sleeve 14, the inner end 15, of which is of a diameter to snugly seat within the chamber 13, and the lower edge 16, of which extends somewhat below the annular guard flange 17, provided on the lower part 18, of the housing 11, whereby screws 19 and 20, threaded through bores 21 and 22, of said guard and wall 23, of the casing and into threaded bores 24 and 25, in the enlarged base 15, of the sleeve 14, whereby the sleeve will be held in fixed position. The wall 26, of the said sleeve is provided with a series of annularly disposed perforations 27, and interposed longitudinal slots 28.

In the upper end 29, of the sleeve 14, is provided a conical recess 30, into which is slidably movable the clamp head 31, of a similar conical formation extending from the arm 32, which arm and head are divided into three sections 33, 34 and 35, by longitudinal slots 36, 37, etc., and are

2

integrally connected at 38, adjacent screw-threaded enlargement 39, of the arm.

The enlargement 15, of the sleeve 14, is internally screw-threaded as at 40, to receive the screw 39, through means of which the jaws 41, 42 and 43, of the head 31, may be moved back and forth in the conical recess 30. The arm end 32', is graduated in diameter as at 44 and 45, whereby the latter enlargement forms a plug for projecting into the bore 46, of a tubular handle 47, and is fixedly secured therein by a screw 48. The end 49, of the handle containing the enlargement 45, seats movably within the terminal end 50, of the housing 11.

From the part 38, out to its terminal 51, the arm 32, is bored in graduated diameters from the smaller inner bore 52, to form gradually increasing seats 53, 54, 55, etc., for the ends 56, of electrodes 57, whereby one electrode of any diameter may readily find its proper seat when projected through the bore 58, in the end wall 59, of casing 11, and the opening 60, within the recess 30, in which head 31, is movably seated. A conductor cord 61, extends through the bore 46, of handle 47, and has its exposed terminal wires 62, soldered into the bore 63, of plug 45.

The casing 11, guard flange 17, and handle 47, are all formed of non-conducting insulation. The other elements of the device, however, are electrodes for conveying electric current from wires 62, to the electrode 57. Upon giving the handle 47, a quarter turn relative to housing 11, the jaws 41 to 43, may either be clamped upon the terminal end 56, of the electrode or upon reverse turn of the handle slightly withdrawing head 31, from the recess 30, the jaws will spring loose from said end 56, and release the member 57, to be dropped from the tool.

From the foregoing it will be seen that I have designed an electric welding tool which through means of the several air circulating chambers 13, 64 and 65, will dissipate the heat generated in the holder before it reaches the handle 47, and also a tool with which electrodes of various diameters may be instantly grasped and released.

It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

Having now described my invention, that which I claim as new and desire to procure by Letters Patent is:

A holder for a welding electrode which includes a tubular handle of non-conducting material, a plug of conducting material fitted into one end of said handle, said plug having an axial bore entering into its inner end for receiving one terminal of an electrical conductor, an integral shank extending axially from the opposite end of said plug, an integral externally screw-threaded collar on the shank intermediate its ends, an annular row of internally stepped welding rod clamp jaws projecting from the end of the shank opposite the plug, enlargements on the free ends of the clamp jaws cooperating to form a substantially conical head, a perforated sleeve of conducting material encircling the clamp jaws in spaced concentric relation therewith, said sleeve having a conically tapered bore adjacent one end for receiving the conical head, an internally screw-threaded socket on the end of the sleeve opposite the conical bore for threaded engagement with the threaded collar, a perforated tubu-

lar housing of non-conducting material fitted over the socket and lying in spaced concentric relation to the sleeve, an annular guard flange extending outwardly from the housing intermediate its ends and radially disposed set-screws entering radial openings in the flange and passing through the socket to impinge upon the collar and hold the sleeve in longitudinally adjusted position on the collar.
